RAY V. WOODS, OF SAN FRANCISCO, CALIFORNIA, ASSIGNOR OF ONE-HALF TO THE WOODRUFF COMPANY, OF SAN FRANCISCO, CALIFORNIA, A CORPORATION OF CALIFORNIA.

CONCRETE BUILDING CONSTRUCTION.

941,837.

Specification of Letters Patent. Patented Nov. 30, 1909.

Application filed July 12, 1907, Serial No. 383,434. Renewed October 2, 1909. Serial No. 520,682.

To all whom it may concern:

Be it known that I, RAY V. Woods, a citizen of the United States, residing in the city and county of San Francisco and State of California, have invented new and useful Improvements in Concrete Building Constructions, of which the following is a specification.

My invention relates to cement or concrete building constructions. Its object is to devise a method and means of building and laying floors, partitions, beams, girders and the like whereby the slabs or elements entering into the structure may be cast separate 10 and at any convenient place away from the building and then hoisted into place and connected together into a permanent structure.

The invention consists of the parts and the construction and combination of parts 20 as hereinafter more fully described and claimed, having reference to the accompanying drawing, in which—

Figure 1 is a cross section of a girder showing my method of bonding the slab sections to each other and to the girder. 25 Fig. 2 is a plan view of the same. Fig. 3 is a side elevation of the same.

A represents a girder or beam which constitutes part of my invention. This beam 30 or girder may be of any suitable length, depth and shape according to its conditions of use. It comprises essentially a cast of concrete in which are embedded the longitudinally extending tension bars 2—2', and 35 the looped shear-bars or stirrups 3 which embrace the tension bars and stand crosswise thereof and project a distance above the top surface of the girder a little less approximately than the thickness of the slab 40 sections 4. As here shown the girder A is substantially T shape, but that is not essential so long as a suitable seat or support is provided for the adjacent ends of said slabs 4, and which seats are here shown as furnished by the lateral flanges α of the beam. There are any desired number of these 45 looped shear bars or stirrups 3 to a beam, arranged at suitable intervals. Passing through the loops and running lengthwise 50 of the beam, are the tie rods 5 to which the tension bars 6 in the slabs 3 are anchored.

The beam element A like the slabs, is originally cast independent and allowed to harden; it is then hoisted into position and 55 is suitably supported at the ends on and

anchored to appropriate abutments as the walls 7. Any desired form of wall anchor for the beam may be employed, such as the anchor bolts 8. Where two sets of tension rods 2—2' are used, the rods of the upper set 2' are bent up and then outward at their ends as shown in Fig. 3; the ends of both sets being hooked and contained within the concrete body of the beam. The slabs like the beam are cast separate from the place 60 which they are designed later to occupy permanently in the building; the tension rods 6 in the slabs being bent upward within and adjacent to the ends of the slabs and projecting a sufficient distance beyond the 65 ends of the slabs to enable them to be suitably tied to or hooked over the anchor rods 5, when the slabs are laid in position. The ends of the slabs purposely do not abut because the end space between the adjacent 70 slabs is designed to form a pocket for a filling of cement or concrete 9; the previously exposed loops 3 and rods 5 and 6 being embedded in the cement filling which later 75 serves to give finish and rigidity to the structure and to prevent displacement of the elements. A union of this character after the cement or concrete filling 9 has set operates 80 to bond the slabs and girder together into one integral structure with every part actually tied to the other by metal; that is, every slab is really tied to every other slab and to its supporting girder by the connections afforded by the several metal bonds 85 3—5 and 6. The metal reinforcing is in 90 fact continuous in this system.

Having thus described my invention, what I claim and desire to secure by Letters Patent is—

In a building construction, the combination of a concrete girder having longitudinal tension-rods extending through the lower portion thereof, said rods being spaced apart, shear-bars of substantially rectangular form having their major axis at right-angles to the major axis of the girder and having their upper ends normally projecting above the top surface of said girder, said girder having lateral flanges at its upper end, slab-sections having their adjacent ends separated from each other and supported upon the flanged end of the girder, the upper ends of said shear-bars entering the space between the adjacent ends of the slab-sections, tension-rods extending longitudinally 95 100 105 110

through the slab-sections and projecting beyond the corresponding ends of the slabs and projecting into the plane of the shear-bars, tie-rods above the girder and extending parallel therewith and through the upper portion of the shear-bars and engaged by the projecting ends of the slab tension-rods, and a filling in the space between the adjacent ends of the slabs and embedding the upper

ends of the shear-bars, the upper tie-rods, 16 and the projecting ends of the slab tie-rods.

In testimony whereof I have hereunto set my hand in presence of two subscribing witnesses.

RAY V. WOODS.
